Attorney

UNITED STATES PATENT OFFICE.

EMMETT FISHER, OF QUINCY, ILLINOIS.

PENCIL HOLDER AND SHARPENER.

Application filed November 15, 1920. Serial No. 424,155.

To all whom it may concern:

Be it known that I, EMMETT FISHER, a citizen of the United States, residing at Quincy, in the county of Adams and State of Illinois, have invented certain new and useful Improvements in Pencil Holders and Sharpeners, of which the following is a specification.

This invention relates to a combined pencil holder and pen-knife and has for its object to provide a simple, neat and inexpensive pencil clip or holder having a blade for sharpening the pencil.

Another object of the invention is to provide a pen-knife consisting of a casing and a sliding blade carried thereby in combination with a pencil holder or clip.

With the above and other objects in view I have invented the device illustrated in accompanying drawings in which:

Figure 1 is an elevational view of my device shown attached to a pencil,

Figure 2 is a similar view taken from another side,

Figure 3 is a perspective view of the device shown detached from the pencil and the blade extended,

Figure 4 is a plan view of the stamped blank from which the device is formed, and

Figure 5 is a detail plan view of the blade.

Like reference characters indicate like parts throughout the following specification and in the several views of the drawings in which 1 indicates a combined casing for the slidable blade 2 and pencil clip. The device is formed from a blank 3 struck from a single sheet of metal and consists of a shank 4 having at one end a pair of laterally extending wings 5 and 6 which are

bent into arcuate formation to form spring clips to engage the pencil 7. The other end of the shank terminates in a body portion 8 which is substantially rectangular the sides 9 and 10 being extended laterally beyond

the longitudinal edges of the shank and are bent over the central portion 11. The body portion after it has thus been formed is bent over the shank 4 whereby the shank 4 provides a fourth side to form a casing for the knife

blade 12 which is slidable in and out of said casing the blade passing out through the slot 13 provided at a juncture of the body portion and shank, said casing being bent upon the shank 4 on a line with said slot. The blade 12 is provided with a square head 14 fitting snugly in said casing and said head has a pin 15 which projects through the slot 16 formed approximately on the line of the fold 17, by means of which projecting pin 15 the blade 12 may be operated slidably in and out of said casing. The square head 14 operating in the casing holds the blade firm when in use. The tongue 18 on the extreme end of the shank 4 is bent over the ends 19 and 20 of the walls 9 and 10 whereby the shank and casing are held together at their outer ends, and the extension 21 of wall 11 is bent over said tongue and forms a closure for the upper end of the casing. The lower end of the shank is bent out as at 22 against the pencil 7, and, due to the resiliency of the metal of which the device is made, forms a spring clip to engage the edge of a pocket in which the pencil is held, thus forming the pencil clip.

Having now described my invention, that which I claim as new and desire to procure by Letters Patent is:

1. A pencil holder and sharpener comprising a casing formed from a single blank including a shank portion having wings extending laterally from opposite longitudinal edges of the shank and bent to provide a pencil clip, one end of the shank being enlarged to provide three sides of a casing and bent upon the shank to provide the fourth side, and a knife blade adjustably mounted in said casing.

2. A pencil holder and sharpener comprising a casing formed from a single blank including a shank portion having at one end means extending laterally thereof and bent to provide a pencil clip, the shank at its other end being enlarged laterally to form a body portion which when folded provides three of the sides of the casing, one of said sides being equipped with a longitudinally extending slot, the blank at the juncture of

the shank and body portion being equipped with the transversely arranged opening, the opposite end of the body portion being provided with a longitudinally extending tongue which is adapted to close one end of the casing formed by folding the shank upon the body portion, and a knife blade adjustably mounted in said casing and projectable through said transverse opening, and having a pin extending through said longitudinally extending slot.

In testimony whereof I affix my signature in the presence of two witnesses.

EMMETT FISHER.
